1,944,354

PHOTOGRAVURE PROCESS AND METAL PLATE THEREFOR

Niels Ludvigsen, Paris, France

Application December 16, 1929, Serial No. 414,437,
and in France December 19, 1928. Renewed
October 25, 1933

12 Claims. (Cl. 95—5.7)

The object of the present invention is to simplify the preparation of photogravure processes as hitherto effected.

The main object of the invention is to avoid the multiple manipulations with dangerous ingredients, such as collodion, nitrate of silver required in photogravure processes hitherto and in consequence to reduce to a minimum expensive material and experienced personnel.

10 The present invention relates firstly to a photogravure process the feature of which is that a grain is formed on a metal plate by impression for example, then after the plate has been sensitized, the image to be reproduced is formed 15 thereon, the printing plate then being finished by the known means of washing, heating and etching.

According to a modification of the invention, an initial grain corresponding to the clear portions of the image is first formed on the metal plate, then the plate is coated with a coating of sensitive gelatine and on this coating a second grain is formed corresponding to the black and half tones, the image to be reproduced being then 25 projected on to the metal plate which is finally washed in such manner as to remove all portions of the gelatine coating not affected by the light, whereas the portions hardened by such light remain and form after etching the dark or half 30 tones of the image.

The modified process may be carried out in the following manner:

A metal plate is prepared and on the bare metal is formed a reticulation or stippling. This 35 plate is then sensitized with a sensitive solution, such as gelatine or albumin treated with bichromate of ammonia. Finally, a second grain corresponding to the half tones is formed by impression on the sensitive coating.

40 On the thus prepared metal plate, is then applied a glass plate bearing an image taken in an ordinary photographic apparatus and which is to be reproduced by photogravure.

The operation is exactly as if a proof is to be 45 taken on paper, the metal plate replacing such paper.

The areas of the sensitive film corresponding to the areas of the glass plate traversed by the light become hardened, whereas the other areas 50 of such film not reached by the light remain water-soluble.

In consequence, when the plate is washed with water, the sensitive film goes away in the areas not hardened by the light and corresponding to 55 the clear portions of the image, the sensitive film

thus leaving bare the initial grain impressed directly on the metal.

On the contrary the areas of the sensitive film hardened by the action of the light are not removed by the washing with water, such areas 60 corresponding with the blacks and half-tones of the image.

By heating, the still remaining sensitive film is definitely fixed. Finally, the plate is etched 65 by any suitable known method.

The invention extends to the above described processes whatever be the arrangements selected for carrying them into effect. Moreover, the invention extends also, as a new product, to metal plates enabling these processes to be carried out 70 in a particularly certain and convenient manner.

These metal plates have the features set forth in the following description and specified in the claims annexed to the end of such description.

Metal plates according to the invention are 75 illustrated by way of example on the accompanying drawing, in which:—

Fig. 1 is a diagrammatic section of a metal plate.

Fig. 2 is an elevation of a metal plate showing 80 the image to be reproduced.

Fig. 3 is a diagrammatic section of a metal plate according to a modification of the invention.

The metal plate illustrated diagrammatically in section in Fig. 1 is a zinc plate 10 having an initial reticulation or stippling 11 obtained by impression, for example, then a sensitive film 12 and finally a second grain 13.

The plate has not yet received the projection 90 of the image.

Assuming that it is desired to reproduce the image of a ship, the zinc plate 10 will present clear zones 15 forming the background of the image, black zones 16 corresponding to the superstructure of the ship and half-tone zones 17 corresponding for example to the hull of the ship. The zinc plate 10 then bears an initial grain corresponding to the clear zones of the image, such initial grain 11 being covered with a sensitive film 12, on which there is a second grain 13 corresponding to the dark zones 16 or to the half-tone zones 17.

The plates to which the invention extends may obviously be very differently constituted, for example:

For a contrasted image the grain 13 of the half-tones 17 is weak; for a nebulous image on the contrary the grain of the clear portions 15 is weak.

This predominance can be carried almost to 110

the point of disappearance of one of the grains, particularly in the case of the formation of printing surfaces without half-tones or without clear portions. In the etching of such plates the initial 5 grain 11 and the second grain 13 will work under very different conditions.

The points of the first grain 11 imposed before the sensitizing are independent of the sensitive film 12. Although it happens thereon, they will 10 fulfil their mission of resisting the acid during etching and later of preventing the inking rollers from penetrating into the clear parts of the image at the time of printing.

The second grain 13 imposed on the sensitive 15 film 12, has, on the contrary, only a photo-chemical action. It disappears when after insulation the image is developed. The sensitive film remains there and it receives the light and will resist the attack of the acid during etching.

20 These plates are commercial articles which can be sold to newspapers, especially provincial newspapers.

I claim:

1. The method of producing photogravure 25 printing surfaces, which consists in providing an acid resisting grain upon the smooth face of a metal plate, said grain having uniform dots regularly disposed, thereafter coating the grained surface with a light sensitive substance, providing a grain on said sensitive surface, said second grain having uniform dots regularly disposed, photographing, developing and etching the plate substantially as described.

2. The method of producing photogravure 35 printing surfaces, as claimed in claim 1, in which the individual points of the second graining are disposed intermediate the points of the first graining, substantially as described.

3. A photogravure process for relief printing 40 with metal plates which consists in forming an acid resisting grain on a smooth uncovered metal plate, this grain having uniform points, regularly disposed, thereafter sensitizing the plate thus prepared, then exposing washing, heating 45 and etching the cliche in the usual way.

4. A photogravure process for relief printing with metal plates which consists in forming an acid resisting grain on a smooth uncovered metal 50 plate, then coating the plate with a sensitive substance, forming a grain on said sensitive layer above the clear portions of the said first grain, bringing thereafter by photographic exposure

upon the plate so prepared the picture to be reproduced, developing the plate and etching the plate by means of an acid.

5. The method of producing photogravure surfaces, which consists in providing an acid resisting grain upon the smooth face of a metal plate, said grain consisting of uniform marks regularly disposed, thereafter coating the grained surface with a light sensitive substance, providing a grain on said sensitive surface, said second grain consisting of uniform opaque marks regularly disposed, thereafter photographically exposing, developing and etching the plate substantially as described.

6. A method as claimed in claim 5 in which the individual marks of the second graining are disposed intermediate the marks of the first graining.

7. A process as claimed in claim 3, in which said grain is formed by printing on the plate with insulating ink.

8. As an article of manufacture a metal plate, said metal plate having a smooth surface provided with a plurality of marks of acid resisting nature and having superimposed thereon a light 100 sensitive layer and further, a plurality of opaque marks provided on said sensitive layer.

9. As an article of manufacture, a metal plate having a smooth surface provided with an acid resisting grain of uniform dots regularly disposed, and a light sensitive layer superimposed thereon, and a second grain of uniform opaque dots regularly disposed and arranged on said sensitive layer.

10. A metal plate as claimed in claim 9 in which 110 the dots of the second graining are disposed intermediate the dots of the first graining.

11. As an article of manufacture, a photogravure printing plate having a printing surface permanently smooth and uninterrupted throughout its extent, an acid resistant grain superimposed directly on said surface and a light sensitive layer superimposed on said grain.

12. As an article of manufacture, a photogravure printing plate having a printing surface 120 permanently smooth and uninterrupted throughout its extent, printed impressions of acid resistant material superimposed directly on said surface and forming a grain thereon and a light sensitive layer superimposed on said grain.

NIELS LUDVIGSEN.
